UNITED STATES PATENT OFFICE.

FRANK L. DYER, OF MONTCLAIR, NEW JERSEY.

COLLAPSIBLE-TUBE PACKAGE

1,413,108.

Specification of Letters Patent. Patented Apr. 18, 1922.

Application filed January 8, 1921. Serial No. 435,971.

To all whom it may concern:

Be it known that I, FRANK L. DYER, a citizen of the United States, residing at Montclair, Essex County, New Jersey, (post office address No. 16 Rockledge Road, Montclair, N. J.,) have invented certain new and useful Improvements in Collapsible-Tube Packages, of which the following is a full, clear, and exact description.

10 My invention relates to new and useful improvements in collapsible tube packages, by which is meant a containing box in which is placed a collapsible tube containing a suitable paste-like substance, such as tooth-paste, 15 shaving-cream, etc. These collapsible tubes, as is well known, are formed of a very ductile metal on suitable dies or plungers, the bottom of the tube being normally open to permit the introduction of the contents, and 20 the tube being then closed by compressing the open bottom together and folding the metal, a sheet metal clip being usually employed to make a tight and strong joint. Obviously the dimension of the bottom thus 25 formed is greater than the diameter of the tube. At the present time it is the general practice to pack these tubes in card-board boxes which are either square or slightly oblong in cross section. Whether square or 30 oblong the boxes are generally designed so that the bottom of the tube will fit more or less approximately the diagonal of the box, but with a square or oblong box it is obvious that the cylindrical body of the tube will 35 never tightly fit the sides of the box. Consequently the present collapsible tube pack- 40 age is more or less flabby and easily distorted notwithstanding the common practice of wrapping circular matter around the tube to make it more nearly fill the box. Making 45 a box in this way wherein the box is obviously too large for the body of the tube is a waste of material, and also a waste of space in packing, besides making an objectionably weak and insecure package.

My improved collapsible tube package is one in which the tube is supported in a containing box, the latter being so constructed that the bottom of the tube will more or 50 less snugly fit one of the diagonals of the box, while at the same time the sides of the box will more or less snugly fit the cylindrical body of the tube. This makes a

stronger and better package, while at the same time less card-board is used in making 55 the box, and the box packs to better advantage in a shipping case.

In carrying out my invention, I make the box diamond shape in cross section, the dimensions being so chosen as to permit the 60 tube to snugly fit the box both as to its cylindrical body and as to its flattened end. By making the package in this way with a diamond shaped box, I produce a package which is capable of better display than a 65 box rectangular in cross-section. In other words, with the latter there are four faces on which printed and display matter can be shown. With a diamond shaped box when standing on end, there are two sets of 70 obliquely disposed display faces, each constituting practically a single face upon which display and printed matter can be shown to much better advantage.

In order that my invention may be better 75 understood, attention is directed to the accompanying drawing forming part of this specification, and in which:

Fig. 1 represents a convenient blank of card-board from which to form my improved 80 box, the lines of folds being shown by dotted lines;

Fig. 2 is an isometric view of the finished box showing the collapsible tube therein in dotted lines; 85

Fig. 3 is a sectional view on the line 3—3 of Fig. 2;

Fig. 4 is a sectional view showing a packing case containing my improved packages; 90

Fig. 5 is a corresponding view showing the size of packing case needed to hold the same number of packages as in Fig. 4, assuming them to be square in cross section.

In all the above views, corresponding parts 95 are represented by the same reference numerals.

The box 1 is provided with four sides as shown at the top and bottom, formed preferably by flaps as shown in Fig. 1. The 100 flaps 2—2 are diamond shaped so as to give that shape to the resulting box, as will be understood. Flap 3 is a usual flap to give strength at the joint, as shown in Fig. 3. Located within the box 2 is the collapsible 105 tube 4 having an extended lower end 5. The

proportions shown in Fig. 3 are those of a standard tube containing a well known brand of shaving cream. It will be seen that by making the box diamond shaped in cross section, the end 5—5 will snugly fit the major diameter of the box, while the cylindrical body of the tube will snugly fit within the four sides of the box. This makes a very much stronger and better package. If the 10 box sets on end, the two sides constitute practically one extended face on which printed and display matter can be shown very advantageously. Referring to Fig. 4, it will be seen that the improved packages 15 can be packed very advantageously in a packing case, and that an actual saving of space can be secured over the old arrangement (Fig. 5) where the packages are square or oblong in cross section. Making the box 20 fit the tube as explained instead of having it much too large for the tube as at present, means a substantial saving in card-board.

Having now described my invention, what

I claim as new therein and desire to secure by Letters Patent is as follows:

25

1. A collapsible tube package comprising a box containing a collapsible tube, the box being diamond shape in cross section, whereby the bottom of the tube will substantially fit its major diameter while the body of the 30 tube will substantially fit its four sides, substantially as set forth.

2. A collapsible tube packing comprising a box containing a collapsible tube, the box being diamond shape in cross section, whereby the 35 bottom of the tube will substantially fit its major diameter while the body of the tube will substantially fit its four sides, said box being formed at its ends with diamond shaped flaps closing said ends, substantially 40 as set forth.

This specification signed and witnessed this 6th day of January, 1921.

FRANK L. DYER.

Witness:

CHARLES C. MARSHALL.
